(57) **CLAIM**

The ornamental design for a bubble toy, as shown and described.

DESCRIPTION

FIG. 1 is a perspective view of an exemplary embodiment of the bubble toy, wherein the lower portions are disposed in a first position;

FIG. 2 is a front view of the bubble toy of FIG. 1;

FIG. 3 is a rear view of the bubble toy of FIG. 1;

FIG. 4 is a right side view of the bubble toy of FIG. 1;

FIG. 5 is a left side view of the bubble toy of FIG. 1;

FIG. 6 is a top view of the bubble toy of FIG. 1;

FIG. 7 is a bottom view of the bubble toy of FIG. 1; and,

FIG. 8 is a perspective view showing the bubble toy with its lower portions disposed in a second position.

The structures shown in broken lines are included for the purpose of illustrating portions of the bubble toy that form no part of the claimed design; the indicia shown in broken lines likewise forms no part of the claimed design.
